UNITED STATES PATENT OFFICE.

ERIK MAGNUSEN, OF PROVIDENCE, RHODE ISLAND, ASSIGNOR TO GORHAM MFG. CO., OF PROVIDENCE, RHODE ISLAND.

DESIGN FOR A LOVING CUP.

Application filed March 21, 1927. Serial No. 21,244. Term of patent 14 years.

To all whom it may concern:

Be it known that I, ERIK MAGNUSEN, a citizen of the United States, residing at Providence, in the county of Providence and State of Rhode Island, have invented a new, original, and ornamental Design for a Loving Cup, of which the following is a specification, reference being had to the accompanying drawings, forming part thereof.

The drawings:

Figure 1 is a top plan view of the loving cup, a portion of the rim being broken away to show a complete handle.

Fig. 2 is a perspective view of the loving cup showing my new design.

I claim:

The ornamental design for a loving cup, as shown and described.

In testimony whereof I have signed my name to this specification.

ERIK MAGNUSEN.
